UNITED STATES PATENT OFFICE.

JULIUS KAHN, OF DETROIT, MICHIGAN.

FIREPROOF FLOOR.

1,101,188.

Specification of Letters Patent. Patented June 23, 1914.

Application filed November 23, 1912. Serial No. 733,034.

To all whom it may concern:

Be it known that I, JULIUS KAHN, a citizen of the United States, and a resident of Detroit, in the county of Wayne and State of Michigan, have invented a new and useful Fireproof Floor, of which the following is a specification.

This invention relates to the construction of fireproof floors and other horizontal slabs, and its object is to produce a structure which can be erected without the use of falsework, which will be in proper condition to receive the flooring without the necessity of concrete filler between the floor sleepers, which shall be light, and which can be erected at moderate cost.

This invention consists in the combination of a series of trussed girders, each formed of two bars of steel properly slotted and expanded, and provided with a groove along its upper edge to receive a floor sleeper, of sheets of ribbed expanded metal secured to the lower flanges of the girders, sheet metal forms resting upon the ribs of the expanded metal between the girders, concrete in the spaces between adjacent forms and extending over the tops of the same and embedding the girders, the top of the concrete being generally level with the tops of the girders, and flooring extending across the top of the concrete and the girders and secured to the sleepers.

This invention further consists in forming the lower tension members of the trussed girders of sufficient strength to act as reinforcing members of the concrete beams in which they are embedded, and therefore of sufficient cross sectional area to carry the total dead and live load on the floor, the inclined members, resulting from the expansion of the intermediate portions of the bars from which the trusses are made, serving to transmit tensional stresses to the concrete, and as diagonals of a trussed girder for carrying the temporary dead load while the floor is being built, and the upper chords of these girders being of such area that they will have ample compressive strength to carry the floor during the time that the concrete of the floor is being constructed, but not sufficient to carry the live load to which the floor is subjected after it is completed.

In the accompanying drawing Figure 1 is a transverse section of a floor constructed according to the present invention. Fig. 2

is a longitudinal section of the same. Fig. 3 is a side elevation of the end of one of the girders on a larger scale than Figs. 1 and 2. Fig. 4 is an end view thereof. Fig. 5 is a side elevation of one end of one of the half-girders from which the girder is formed. Fig. 6 is an end view thereof. Fig. 7 is a section on the line 7—7 of Fig. 3. Fig. 8 is a section on the line 8—8 of Fig. 5.

Similar reference characters refer to like parts throughout the several views.

The truss or girder shown in the drawing is similar to that shown in my co-pending application No. 733,035, filed Nov. 23, 1912. These trussed girders are formed of two expanded metal members, that are formed and joined in a manner hereinafter indicated. Each of the members comprises a half compression chord, a half tension chord, two half-diagonals 2 and 3, and a plate 100 or 101 that is formed integral with the member and joins the ends of the half-diagonals. The half-compression chord comprises a laterally extending flange 4, an outturned flange 5, and an in-turned web 30, the flange 5 being preferably formed near its outer edge with a longitudinal rib 31, and the web 30 being preferably formed near its inner edge with a longitudinal rib 32. The half tension chord 1 comprises a laterally extending flange 35 and an in-turned web 36, the latter being preferably provided with a longitudinal rib 37 along its inner edge.

Formed integrally with the half chords of one of the expanded metal members are the inwardly extending clips 7 and 8, and formed integrally with the other expanded metal member are similar clips also designated 7 and 8.

As indicated in Fig. 1, some of the clips (preferably alternate clips) may be formed on each of the half compression chords, and in a similar manner some may be formed on each of the half tension chords; but it is obvious that all of the clips might be formed on one of the half chords if desired.

The plates 100 are formed integral with the adjacent ends of the half-diagonals 2 and 3 of one of the expanded metal members, and the plates 101 are integral with the adjacent ends of the half-diagonals of the other member, and these plates extend longitudinally somewhat beyond the ends of the corresponding half-diagonals, as indicated at 102.

The two expanded metal members are as-

sembled in reverse relation to each other as shown, and the clips 7 and 8, that are integral with one of the expanded metal members, are bent to inclose the edges of the webs 30 and 36 and the ribs 32 and 37, respectively, thereon. The longitudinal extensions 102 on the plate 100 are bent to inclose the edge of the plate 101, and the extensions 102 of the plate 101 are likewise bent to inclose the edge of the plate 100. In this manner the members are rigidly secured together.

In the groove or trough formed by the horizontal parts 4 and vertical parts 5 of each girder, a wooden sleeper 11 may be placed, which may be held in position by sheet metal clips 12 spaced at proper intervals. Sheets of metal-lath 14 provided with upwardly extending ribs 15 may be secured against the bottom flanges 1 by means of wires 16 as shown in the drawings. Upon these sheets of ribbed metal are placed forms of sheet metal, preferably constructed with corrugated sides 18 and tops 19, to produce air spaces in the floor. Concrete 20 is then placed between adjacent forms so as to embed the girders, and this plastic material will flow down between the ribs 15 of the metal lath and around the lower flanges 1 of the girders, as indicated at 17 in Fig. 1. The concrete extends over the tops of these metal forms and its upper surface is preferably level with the top of the sides 5 of the troughs in which the sleepers 11 rest. The flooring 21 may then be nailed directly to the sleepers 11.

By forming the tops of the girders trough-shaped, sufficient metal is employed to more than equal the compressive strength of the concrete displaced. The floor is therefore not weakened by the embedding of the sleepers 11 therein. The usual concrete filling employed between floor sleepers is saved as the floor 21 can be secured directly against the concrete 20 or against a sheet 22 of paper or other substance adapted to act as a cushion between the floor and the concrete if desired. It will be understood, of course, that this sheet can be omitted. These girders are preferably so constructed that the top chords have sufficient compressive strength to permit the girders to carry the floor until the concrete has set, after which the top chords and the concrete will act together as the compression member of a reinforced concrete beam. The ribbed metal lath can be made with a mesh of sufficient fineness to prevent the passage of concrete, and as the ribs of this metal lath are of sufficient stiffness to carry the sheet metal forms and the concrete resting thereon through the short span between the edges of the adjacent forms, it will be apparent that no falsework is necessary in the construction of the floor illustrated. The high expense of this falsework and also

of the usual cinder concrete employed to fill the spaces between the floor sleepers are therefore saved, and because of this saving of the concrete and its weight, a saving in the steel employed to reinforce the concrete joists of the floor results. No falsework being necessary, the floor can be erected in much less time than is usually required, so that this construction is one of great cheapness. Furthermore, as the floor sleepers are embedded in the concrete joists, a saving in thickness of the floor is accomplished. If desired, a layer 24 of plaster may be applied to the lower face of the metal-lath 14.

I claim—

1. As an article of manufacture, an expanded metal member comprising a half compression chord, a half tension chord, two half diagonals, and a plate joining the ends of the half diagonals, said plate being extended longitudinally beyond the ends of the half diagonals. 80

2. As an article of manufacture, an expanded metal member comprising a half compression chord, a half tension chord, two half diagonals, a plate joining the ends of the half-diagonals and clips extending inwardly from one of the half-chords. 90

3. As an article of manufacture, an expanded metal member comprising a half compression chord, a half tension chord, a series of half-diagonals in pairs, means for joining the half-diagonals of each pair at their ends, and clips extending inwardly from each of the half-chords. 95

4. As an article of manufacture, an expanded metal member comprising a half compression chord, a half tension chord, a series of half-diagonals, and a plate joining the ends of the half diagonals of each pair, 105 said half compression chord including a laterally extending flange, an inwardly extending web, and clips extending inwardly from the web, and said half tension chord including a laterally extending flange, an inwardly extending web and clips extending inwardly from the web. 110

5. As an article of manufacture, an expanded metal member comprising a half compression chord, a half tension chord, and 115 two half-diagonals joined at their ends, said half compression chord including a laterally extending flange, an outwardly extending flange, an inwardly extending web, said half tension chord having a laterally extending flange and an inwardly extending web, one of the half-chords being provided with inwardly extending clips.

6. As an article of manufacture, an expanded metal member comprising a half compression chord, a half tension chord and two half-diagonals joined at their ends, each of said half-chords including a laterally extending flange and an inturned web having a longitudinal rib thereon, and one of the 120

half-chords including inwardly extending clips.

7. A girder composed of two members, each comprising a half compression chord, a half tension chord, two half-diagonals, a plate joining the ends of the half-diagonals, and clips extending inwardly from one of the chords, said members being arranged in reverse relation to each other, the clips on each of the members being bent to engage with portions of the other member, and portions of each of the plates being bent to engage with the other plate to secure the members rigidly together.

15 8. A girder composed of two members, each comprising a half compression chord, a half tension chord, two half-diagonals and a plate joining the ends of the half-diagonals, said plate being formed to extend longitudinally beyond the ends of the half-diagonals, said half chords each comprising a laterally extending flange and an inwardly extending web, clips on one of the half compression chords and clips on one of the half tension chords, said members being assembled in reverse relation to each other, the clips on the half compression chord being bent to engage with the other half compression chord, the clips on the half tension chord being bent to engage with the other half tension chord, and the longitudinal extension of each of the plates being bent to engage the other plate to secure the members rigidly together.

35 9. A girder comprising two members, each comprising a half tension chord, a half compression chord, and two half-diagonals joined at their ends, the half compression chords each including a laterally extending flange, an outwardly extending flange attached to the edge thereof, an inwardly ex-

tending web and clips extending inwardly from the web, said half tension chords each including a laterally extending flange, an inwardly extending web, and clips extending inwardly from the web, said members being arranged in reverse relation to each other, the clips on each of the half-chords being bent to engage with the other half-chord, and the ends of all the half-diagonals being secured together.

10. A new article of manufacture consisting of a girder composed of two bars properly slotted and expanded to form top and bottom chords connected by means of members inclined in the same direction from both chords and united substantially midway between the chords, the bars each having integral tongues adapted to be bent over and around adjacent parts of the companion bar, the top edges of the bars being separated to form a trough at the upper edge of the girder.

25 11. A girder composed of two members, each comprising a half compression chord, a half tension chord, two half-diagonals, a plate joining the ends of the half-diagonals, and clips extending inwardly from one of the chords, said members arranged in reverse relation to each other, the clips on each of the members being bent to engage with portions of the other member, and means for securing the plates rigidly together.

30 In testimony whereof I have signed this specification in the presence of two subscribing witnesses.
